UNITED STATES PATENT OFFICE.

RUDOLPH COOPERSMITH, OF TORONTO, ONTARIO, CANADA.

SOFA-BED.

1,272,626.

Specification of Letters Patent. Patented July 16, 1918.

Application filed March 25, 1916. Serial No. 86,622.

To all whom it may concern:

Be it known that I, RUDOLPH COOPERSMITH, of the city of Toronto, in the county of York, in the Province of Ontario, Canada, have invented certain new and useful improvements in Sofa-Beds, of which the following is the specification.

My invention relates to improvements in sofa beds and the object of the invention 10 is to devise a bed of this class which is compact, in which the foot portion of the bed lies within the frame back of the lounge behind the upholstered back thereof and yet separated therefrom, in which the bed may 15 be unfolded or refolded by a single operation with a minimum amount of effort whereby the lounge back is carried from a position in front of the folded foot portion to a position beneath the unfolded center portion of 20 the bed or the seat portion of the lounge and at the same time so forming the bed that the mattress is independently removable therefrom and separated from the upholstered seat and upholstered back and it 25 consists essentially of a lounge frame, a bed frame swung within the lounge frame and divided into sections swingably connected together, a seat portion for the lounge secured to the back of the center bed section, a supporting leg for the outer end of such center bed section, a bracket extending inwardly therefrom, a lounge back swung in proximity to its lower edge upon the bracket, a substantially right 30 angular lever swung on the sides of the lounge frame in proximity to the end of the short arm and connected to the end of the long arm in proximity to the opposite or upper edge of the lounge back, a resilient 35 connection between the extreme end of the short arm of the lever and the lounge frame whereby the weight of the bed is lifted during the upward throw and supported during the downward throw as it is unfolded or refolded as hereinafter more particularly explained by the following specification.

Figure 1, is a general perspective view of my sofa bed folded to form a lounge.

Fig. 2, is a cross sectional view through Fig. 1 showing the bed in the folded position.

Fig. 3, is a similar view to Fig. 2 showing the bed partially unfolded.

Fig. 4, is a similar view to Figs. 2 and 3 showing the bed completely unfolded.

Fig. 5, is an enlarged perspective detail of

one end of the bed frame and its supporting structure.

Fig. 6, is a further enlarged detail of the swinging connection between the sections of 60 the bed frame.

Fig. 7, is a plan section of the upper joint shown in Fig. 6.

Fig. 8, is a longitudinal section on line x—y Fig. 4 intermediately broken away of 65 its length.

Fig. 9 is an enlarged perspective view of the resilient lifting means.

Fig. 10 is a plan section on line x'—y', 70 Fig. 9.

Fig. 11 is a perspective detail of one of the connecting brackets.

In the drawings like letters of reference indicate corresponding parts in each figure.

1 indicates the lounge frame comprising 75 the end members 2 and 3 and back board 4. The back board 4 is connected to the portions 2 and 3 by brackets 5 and 6. The brackets 6 are permanently secured to the side portions 2 and 3 and are detachably secured to 80 the back board by bolts 6*. The brackets 5 are permanently secured to the side portions 2 and 3, the right angular inwardly extending flange being provided with a vertical slot 5*. 5' indicates a stud extending in- 85 wardly from each end of the back board 4 and provided with a suitable head so as to engage with the vertical slot 5* when slid vertically thereinto. By this means the side portions 2 and 3 are connected together by 90 the back board 4. 7 indicates a bracket which extends inwardly from each of the side portions 2 and 3 in proximity to the back thereof, such bracket being provided with a notch 7* for a purpose which will 95 hereinafter appear.

8 indicates a bracket (see Fig. 5). The brackets 8 extend from each of the side portions 2 and 3 in proximity to the front thereof and are provided with a vertical notch 100 8* for a purpose which will hereinafter appear. 9 indicate rectangular frames located at the inside of each of the side portions 2 and 3 and comprising the vertical angle bars 9* and 9* connected together at the bottom by 105 the angle bar 9* having the horizontal flange 9* thereof turned outwardly. 9* indicates a flat bar which is connected at one end to the upright angle bar 9* and is provided at its opposite end with an inturned portion 9* 110 secured to the outwardly extending flange of the vertical bar 9*. The outwardly ex-

- tending flange 9⁴ of the angle bar 9³ rests in the notch 7² of the bracket 7. 10 indicates a stud extending inwardly from the outwardly extending flange of the bar 9².
- 5 When the flange 9⁴ is inserted in the notch 7² the stud 10 is slid vertically down into the vertical notch 8^x of the bracket 8. The frames 9 located at each end of the lounge are supported upon the portions 2 and 3 in
- 10 a similar manner and are connected together by the longitudinally extending angle bars 11 and 12. 13 indicates the bed frame divided into head sections 14 and 15, center section 16 and foot section 17. The side bar 15^x of the section 15 is notched at 15' and 15^x as shown in Fig. 6 forming lugs 15³ and 15⁴ to which are pivoted the side bars 14^x and 16^x the end of the side bar 14^x being also provided with a notch 14' as shown in this
- 15 figure. The end of the side bar 16^x adjacent the side bar 15^x is provided with an open ended slot 16³. 15^{1x} is a bar secured to the side bar 15 in alinement with the slot 16³. This construction allows of the side 16^x being swung freely forward from the position shown in Fig. 6. When the side bar 16^x is swung in the opposite direction it engages the bar 15^{1x} to carry the bars 15^x and 14^x upward.
- 20 I merely describe this construction in order to make the operation of my device clear but do not lay claim to it as new as it is the common construction usually employed in this class of bed.
- 25 The bed frame 13 is pivoted at 13^x to a bracket 9⁷ secured to each bar 9². 18 indicates a bracket extending upwardly from each bar portion 14^x. 19 indicates a link connecting the upper end of the bracket 18
- 30 with the bar 9³ of the frame 9. 20 indicates the seat portion of the lounge which is of upholstered construction and supported upon the frame 21 connected to the side bar 16 of the bed frame. 22 indicates a longitudinal
- 35 bar extending between the portions 2 and 3 and suitably connected thereto. 23 indicates a flap of flexible material extending from the upholstered seat portion 20 to the longitudinal bar 22 to which it is secured. 24 indicates a leg depending from each of the side bar portions 16 of the bed frame 13 in proximity to the outer end of such side bar portions. 25 indicates a bracket extending inwardly from each of the legs 24.
- 40 26 indicates the upholstered back body of the lounge provided with end bars 27 pivotally secured at 28 to the brackets 25. 29 indicate right angular levers comprising the short arm 29^x and the long arm 30. The short arm 29^x of each lever 29 is pivoted intermediately of its length at 31 to the top bar 9⁵ of each side frame 9. The end of the long arm 30 of the right angular lever 29 is pivotally connected at 32 to the bar 27. 33 indicates a bar secured to each of the bottom
- bars 9³ of the frames 9. 34 indicates a spiral spring connected at one end to the extreme end of the short arm 29^x of the lever 29 and at the opposite end to the bar 33.
- 35 indicates an angle bar portion secured to the leg 24. 36 indicates a bar forming an extension to each side bar 16 of the bed frame. The side bars of the foot section 17 are pivotally secured at 17^x between the bar portion 35 and the bar portion 36. 37 indicates a supporting leg for the outer end of the foot section 17 of the bed. The leg 37 is pivotally connected to the side bars of such foot portion at 37^x. 38 indicates a link pivotally connected at one end to the supporting leg 37 intermediately of its length and at the opposite end to the extreme end of the bar 36. 39 indicates a strip which is secured to the outer end of the foot section 17 and designed to form a top or finish for the lounge back when the bed is folded against the back board as shown in Fig. 2 of the drawings. 40 indicates the ordinary mattress which is supported in a suitable manner upon the bed frame 13 so as to fold with the bed frame when carried from a horizontal to the folded position. 41 is a vertical angle bar secured to the bars 9³ and 9⁵ and spaced apart from the bar 9² to form a vertical guideway 42. 43 is a slide bar located in the guideway. 44 and 45 are plates riveted to the bar 43 at each side and forming a vertical edge groove into which the opposing edges of the angle bars 9² and 41 extend. The lower end of the bar 43 is out-turned and the upper end of the out-turned flange of the angle bar 41 is inturned. 46 is a tension spring connected to the out-turned and inturned portions of the bars 43 and 41. 47 is a roller journaled on a pin 48 extending from the bar 16^x. The roller 47 engages the upper end of the slide bar 43 whereby the bar is depressed during the closing of the bed.
- Having described the principal parts involved in my invention, I will briefly describe the operation of the same. When it is desired to unfold the bed from the position shown in Fig. 2 to the position shown in Fig. 4 all that it is necessary to do is to grasp the portion 39 connected to the foot portion 17 of the bed and draw it outwardly and upwardly in an arc-shape direction. This movement is aided by the tension of the spring 46 drawing upon the lower end of the slide bar 43 exerting an upward pressure on the upwardly moving portion of the bed. Simultaneously with this upward movement of the foot portion of the bed the upper edge of the back portion of the lounge is carried in a circular path by the long arm of the lever 29 around its center of swing formed at 28 thereby carrying it from the position shown in Fig. 2 to the position shown in Fig. 3 against the upholstered seat portion 20 of the lounge. Such back por-

tion remains in this position as the bed is carried to the completely unfolded position. As the foot portion of the bed drops from its highest position shown in Fig. 3 to the horizontal position shown in Fig. 4 a tension is exerted by the spring 34 which resists the downward movement of the bed thereby taking all strain from the operator in carrying the bed to the horizontal position.

When the bed is refolded the reverse of this operation takes place, the tension of the spring shown in the position in Fig. 4 tending to counterbalance the weight of the foot portion of the bed as it is removed to the highest position and as it drops to the closed position against the back board 4 of the lounge frame the roller 47 engages the slide bar 48 the weight then being carried by the spring 46.

From this description it will be seen that I have devised a sofa bed in which a minimum amount of exertion is necessary to open the bed to an unfolded position or refold it to a closed position and at the same time providing a bed in which the mattress is entirely separate from the upholstered portions of the lounge and, therefore, independently removable therefrom and in which the back of the lounge seat is carried with the bed from its normal position, when forming the back of the lounge, to a position beneath the seat portion of the lounge when the bed is in its unfolded position.

What I claim as my invention is.

1. In a sofa bed, the combination with the lounge frame, of a folding bed pivotally mounted between the side portions of the lounge frame and comprising a plurality of sections hingedly connected together, one portion disposed normally in a vertical position another in a horizontal position and another portion folded thereunder, a lounge seat secured to the upper side of the horizontal portion of the bed frame, legs for supporting the outer end of such horizontal portion when in the unfolded position, a bracket extending inwardly from each of the supporting legs, a lounge back pivotally attached to such brackets in proximity to its lower edge, and means for swinging the upper portion of such back in a circular path as the bed is unfolded to carry such back portion beneath the seat portion of the lounge.

2. In a sofa bed, the combination with the lounge frame, of a folding bed pivotally mounted between the side portions of the lounge frame and comprising a plurality of sections hingedly connected together, one portion disposed normally in a vertical position another in a horizontal position and another portion folded thereunder, a lounge seat secured to the upper side of the horizontal portion of the bed frame, legs for supporting the outer end of such horizontal portion when in the unfolded position, a

bracket extending inwardly from each of the supporting legs, a lounge back pivotally attached to such brackets in proximity to its lower edge, means for swinging the upper portion of such back in a circular path as the bed is unfolded to carry such back portion beneath the seat portion of the lounge, and means connected to said means for counterbalancing the weight of the bed as it passes from the folded to the unfolded position.

3. In a sofa bed, the combination with the lounge frame, of a folding bed pivotally mounted between the side portions of the lounge frame and comprising a plurality of sections hingedly connected together, one portion disposed normally in a vertical position another in a horizontal position and another portion folded thereunder, a lounge seat secured to the upper side of the horizontal portion of the bed frame, legs for supporting the outer end of such horizontal portion when in the unfolded position, a bracket extending inwardly from each of the supporting legs, a lounge back pivotally attached to such brackets in proximity to its lower edge, means for swinging the upper portion of such back in a circular path as the bed is unfolded to carry such back portion beneath the seat portion of the lounge, said means comprising an elbow lever having one arm pivotally supported intermediate of its length to the lounge frame and the other arm pivotally connected to the lounge back in proximity to its upper edge, and a tension spring connecting the extreme end of the pivotally supported arm to the lounge frame.

4. In a sofa bed, the combination with a stationary frame, of a foldable bed bottom pivotally connected to said frame and comprising a series of sections connected together, a sofa back movably carried by the bed bottom, a substantially L-shaped lever having its normally horizontal arm pivotally mounted in the frame intermediate of its length and having its vertical arm pivoted to said back, and counter-balancing means connected to the end of the horizontal arm.

5. In a sofa bed, the combination with the lounge frame, of a folding bed swung between the sides of the lounge frame and comprising a series of sections hingedly connected together, an elbow lever having its normally horizontal arm pivoted to the frame intermediately of its length and its vertical arm supporting the seat, and counterbalancing means connected to the outer end of the normally horizontal arm.

6. In a sofa bed, the combination with the lounge frame, of a bed frame and a seat section comprising a plurality of sections hingedly connected together and a lounge back, and means for supporting and carry-

ing such back to automatically pass from its normal position to a position beneath the unfolded seat section and approximately parallel thereto during the unfolding operation.

7. In a sofa bed, the combination with the lounge frame, lounge back and lounge seat section, of a bed frame comprising a plurality of sections hingedly connected together, said lounge seat section being invertibly carried by one of said sections, and means operated by the unfolding of the bed to swing the lounge back against the seat section as the seat section is inverted by the simultaneous operation of unfolding the bed whereby the lounge back is carried into a position beneath and against the lower face of the seat section when in the unfolded position.

8. In a sofa bed, the combination with the lounge frame, of a bed frame pivotally mounted within the lounge frame and provided with a head, center and foot sections,

a lounge seat carried by the center section, a lounge back pivotally carried by the bed frame, and means for swinging and maintaining the lounge back against the seat section as the bed is unfolded.

9. In a sofa bed, the combination with the main frame, of a folding bed swung in the frame and comprising a plurality of sections hingedly connected together, one forming a foot section including legs, a substantially L-shaped lever having its horizontal arm pivoted to the main frame intermediate of its length, a lounge back to the upper end of which the vertical arm of the lever is connected, means for pivotally connecting the lower portion of the lounge back to the legs of the seat section, and a counterbalance connected to the opposite end of the lever.

RUDOLPH COOPERSMITH.
